TROUSERS

Basil M. Havens, Bastian, Va.

Application April 23, 1948, Serial No. 145,920

Term of patent 14 years

(Cl. D3—17)

To all whom it may concern:

Be it known that I, Basil M. Havens, a citizen of the United States, residing at Bastian, in the county of Bland and State of Virginia, have invented a new, original, and ornamental Design for Trousers, of which the following is a specification, reference being had to the accompanying drawing, forming part thereof.

Figure 1 is a front perspective view of a pair of trousers, showing my new design, and

Figure 2 is a rear perspective view thereof.

I claim:

The ornamental design for trousers, as shown.
BASIL M. HAVENS.
